UNITED STATES PATENT OFFICE

WILBUR F. SANDERS, OF CHICAGO, ILLINOIS

DESK PAD

Application filed December 23, 1929. Serial No. 415,885.

My invention relates to a desk pad and more particularly to a desk pad having supporting devices for writing paraphernalia.

The ordinary desk pad has a plain flat surface, the only utility of which is to provide a smooth writing surface underneath thin sheets of paper, which may be placed thereon during writing.

An object of my invention is to provide a new and improved desk pad.

A further object is to provide a desk pad having supporting means for various writing paraphernalia such as pencils, clips, and the like.

15 A further object is to provide a desk pad having means for supporting a penholder for a fountain pen thereon.

Other objects and advantages will appear as the description proceeds.

20 In accordance with the general features of the invention, I provide a desk pad of flexible material which is increased in thickness at certain portions to render a less flexible support due to the thickness of the material 25 in these portions.

Referring to the drawings, Fig. 1 is a perspective view of a desk pad embodying my invention, shown in position upon a desk,

30 Fig. 2 is an enlarged sectional view taken on line 2—2 of Fig. 1, and,

Fig. 3 is an enlarged sectional view taken on line 3—3 of Fig. 1.

35 My desk pad may be made of any suitable material. However, I prefer to use a flexible material which offers sufficient frictional resistance to maintain it in position on the desk and also prevent paper or stationery from readily sliding over the surface during writing.

40 A suitable material having these characteristics is described in my Patent No. 1,709,544 of April 16, 1929. This material is a filled vulcanized rubber compound properly processed and treated to bring out the desired

45 characteristics. The basis of the composition is rubber and clay, some of the rubber may be reclaimed, and so acting somewhat as a filler, the principal binding depending upon new rubber. I believe that the clay being refractory has a great deal to do with the non-burn-

ing characteristic of this material, and it also has an effect upon the degree of hardness, which is controlled to provide the proper writing quality of the pad.

The writing pad has a flat portion 9, which forms the writing surface. Along the sides of the flat portion are raised portions 11 of greater thickness than flat portion 9. The raised side portions are provided with a longitudinal channel 12 for receiving and retaining pencils or other instruments used in writing.

Spaced slightly from each end of the longitudinal channel is a circular depression 13, which serves as a retainer for paper clips, pen points, or other materials which often are otherwise left promiscuously upon the desk.

The pad is provided with a raised or relief portion 14 which forms the base for a pair of penholders 15. The penholders are mounted upon a circular plate 16 having a pair of spaced upwardly extending supports 17, provided with concave indentations for receiving a ball 18, at the end of a retainer 19. Ball 18 is retained in the concave depressions of supports 17, and forms therewith a universal

50 joint permitting the retainer 19 to be held at any suitable angle. The retainer or cap 19 is adapted to receive a fountain pen 21, or the like. Extending downwardly from plate 16 is a threaded stem 22, which passes through an aperture 23 in the base to anchor the pen holders in the base. Aperture 23 is

55 preferably counter-sunk so that when nut 24 is threaded on stem 22, to anchor the pen holders, it does not project below the lower surface of the base. Base 14 is preferably spaced a small distance from the edge of the pad, leaving a flat portion 25 rearwardly of the base. This is done for purposes of convenience of manufacture. The molds are so

60 constructed that the overflow is formed on the flat portion of the edge of the pad from which it may be readily removed, obviating the necessity of trimming the base, which might mar its appearance.

65 It will thus be seen that my pad provides supporting and retaining means for all the instruments usually employed in writing. On account of the flexibility of the material I have increased the thickness of the pad in

those portions where a lesser degree of flexibility is required. If, for instance, the pen-holders 15, were secured to the flat portion of the pad, the weight of the pens might overbalance the resistance to strain or bending of the material of the pad. The weight of the portions of increased thickness is also advantageous in counteracting the weight of the pens to retain the base 14, in position. The added weight in the raised portions 11 along the side of the pad serves to maintain the pad in position upon the desk.

It will be understood that the embodiment of my invention described and illustrated, is merely illustrative of the invention and that many modifications may be made therein without departing from the spirit and scope of the invention.

What I claim is new and desire to protect by Letters Patent of the United States is:—

As a new article of manufacture, a flexible desk pad of a rubber clay composition having a substantially rectangular outline, said pad being adapted to lie flat on a desk, a relief portion within the confines of said rectangle and adjacent one edge of the pad, said relief portion being of the same material as the pad and integrally formed therewith, a writing appliance holder secured to said relief portion, the weight of said relief portion being sufficient to balance the weight of a writing appliance and the holder therefor, whereby the flexible pad is prevented from curling up, due to the unbalancing weight of the writing appliance.

In witness whereof, I hereunto subscribe my name this 13th day of December, 1929.

WILBUR F. SANDERS.
